UNITED STATES PATENT OFFICE.

DAVID G. McCAA, OF PALO ALTO, CALIFORNIA.

SIGNALING SYSTEM.

Application filed May 2, 1922. Serial No. 557,911.

To all whom it may concern:

Be it known that I, DAVID G. McCAA, a citizen of the United States, residing in Palo Alto, county of Santa Clara, State of California, have invented new and useful Improvements in Signaling Systems, of which the following is a specification.

My invention relates to signaling systems, and more particularly to such systems as radio and other systems in which it is desirable to eliminate the effects of static, strays, electrical atmospheric disturbances, or in general, any disturbing electrical effects.

My invention resides in a method of and apparatus for eliminating disturbing effects of the character above referred to, including the effects due to or representing undesired signals.

In accordance with my invention, the signal-representing energy has or is caused to produce a substantially uniform or definite frequency, preferably an audio frequency, which causes or controls vibration, preferably at the same frequency, of a tangible or physical mass or structure, having suitable characteristics, which in turn directly, or preferably indirectly through a second tangible or physical mass or structure physically or mechanically coupled with the first mentioned mass or structure, generates or causes fluctuation of amplitude of a current which, preferably after amplification or other modification, operates or controls a translating instrument for reproducing the signal, as in the form of sound or otherwise.

My invention resides in the method and apparatus hereinafter described and claimed.

For an understanding of my method, and for an illustration of some of the various forms my apparatus may take, reference is to be had to the accompanying drawings, in which:

Fig. 1 is a diagrammatic view of electrical circuits associated with apparatus, shown in elevation, embodying my invention.

Fig. 2 is a similar view of a modification.

Fig. 3 is a diagrammatic view of a modified form of electric circuit utilizable with my invention.

Figs. 4 and 5 are end and side elevations, respectively, of a portion of my apparatus.

Fig. 6 is a side elevational view of mechanical damping means.

Fig. 7 is a diagrammatic view of a multi-

section band device and the associated electrical driver and generator.

Fig. 8 is an elevational view of a reed structure with associated diagrammatic representations of the electric driver and generator.

Fig. 9 is an elevational view of a single section band device or equivalent with diagrammatic representation of the electric driver and generator.

Fig. 10 is a longitudinal sectional view, partially in elevation, of air-coupled members with which are associated the electric driver and generator shown diagrammatically.

Referring to Fig. 1, A represents the antenna or other absorption structure of a radio receiving station, or, in general, represents any conductor from which the signal-representing energy is received, as in a radio system, as aforesaid, or in a system employing a conductor or conductors between stations and traversed by current of suitable frequency, and more particularly, a high frequency as in carrier wave systems.

For brevity, and because of preference, my invention will be described as utilized in connection with a radio receiving system in which the signals are transmitted by electro-radiant energy of high frequency, and more particularly, high frequency sustained or continuous waves.

By way of example, there may be connected between the antenna A and the earth or counter-capacity E the variable inductance L and the variable primary P of an oscillation transformer, L and P being shunted by the variable tuning condenser C. Coupled to the primary P is the secondary S shunted by the variable tuning condenser C¹, the difference of potential at whose terminals is impressed, as through the condenser C², shunted by a high resistance R, upon the grid g and cathode or filament f of a thermionic detector and amplifier V having in addition to the aforesaid grid and cathode the usual anode or plate a. The filament f is maintained incandescent by current, whose magnitude is controlled by the variable resistance r, from the battery b. The anode circuit has the battery or other suitable source of current B and the primary p of an audio frequency transformer whose secondary is s.

Related to the receiving apparatus as de-

scribed in any suitable manner is a source of high or radio frequency current D, which, in the example illustrated, is coupled to the grid circuit of the vacuum tube V by the 5 transformer e.

As well understood in the radio art, if the signals in transmission are represented by undamped or sustained waves, or waves in trains with suitably small decrement, such 10 received waves react with the current waves from the source D to produce beats whose frequency is the difference between the frequencies of the received energy and of the current from the source D. Generally, the 15 beat frequency may be anything suitable or desirable, but in the example illustrated is of audio frequency, as for example, of the order of 1000 per second. The result is that in the secondary s there appears a current of 20 audio or beat frequency, and this secondary circuit is preferably attuned to such audio or beat frequency by means of the variable condenser C³. In the secondary circuit are connected the coils or winding d, d surrounding 25 the soft iron cores e, e disposed, respectively, upon the opposite poles of the permanently magnetized member or permanent magnet h. Pivoted at i is a soft iron armature j supported by the upstanding members 30 k, this structure being more clearly shown in Figs. 4 and 5, hereinafter referred to. A spring m of any suitable material, as phosphor bronze, engages with its upper end upon the upper side of the armature j and is 35 secured or supported at its lower end upon one of the poles n of the cores e. Carried by or supported on the armature j on its end opposite the spring m is the light rod o, which is suitably attached to or merely 40 pressed against the primary band F, which may be of steel or other suitable metal, as bronze, brass, etc., or which may be of any suitable non-metallic material, as celluloid, fibre, wood, formica, and the like. 45 The band F may be of any suitable cross section or shape, and may be in the form of a ribbon or band, a wire or spring of circular or other cross section, etc. Herein, however, the term "band" is used generically to cover 50 all suitable forms, including the ribbon or true band form.

Suitably joined to the band F or preferably, as indicated, integral therewith or forming a continuation thereof, is the secondary band G, the bands F and G being 55 secured at one end at q and at the other end held in a clamp t having the threaded shank u on which is threaded the thumb nut v, turning of which changes the tension on the bands F, G to tune them or give them a desired or definite frequency or frequencies. The bands F, G are stretched over the upper 60 ends of the blocks or members w, forming fulcra, frets, or the like determining the vibration lengths of the band sections F and G. 65

The sections F and G preferably vibrate at the same frequency or have the same natural period, and this is obtainable, when F and G are similar, in the sense of vibrating strings or bands, when the lengths of these sections between fulcra are equal. It will be understood, therefore, that preferably the member w engages the band mid-way between the terminal members w, w. 70

Associated with the band section G is a light rod o and an armature and magnet system similar to that described in connection with the band section F. 75

A second band structure comprising primary and secondary sections F¹ and G¹ may be employed in cascade with the above described band structure comprising sections F and G. With the band sections F¹ and G¹ are associated, respectively, magnet systems corresponding to those associated with the sections F and G. The coils d of the magnet system associated with the band section G are connected in circuit with the coils d of the magnet system associated with the band section F¹, and a variable condenser C⁴ is 80 preferably connected in shunt to them for tuning their circuit to the frequency of the band sections G and F¹, and in particular to the frequency of the band section G. The coils d of the magnet system associated with the band section G¹ are connected in circuit with the primary x of an audio frequency transformer whose secondary is y. The circuit of the coils d and primary x is attuned 85 by the condenser C⁵ to the frequency of the current in that circuit or the frequency of the band section G¹. The transformer secondary y is connected, preferably through one or more thermionic or other amplifiers H, with the translating instrument T, which may be a telephone receiver when the signals are to be reproduced as sounds, or which may be any other suitable or convenient type of translating instrument or a relay controlling the signal translating instrument or other 90 device of any suitable character whatsoever. 95

The operation is as follows:

The current of audio frequency delivered by the secondary s causes the armature j of the magnet system associated with the band section F to vibrate at like frequency, thereby setting the band section F into vibration at the same frequency, the natural period of the band F preferably being equal to the natural period of the circuit of the secondary s. The band section F is a tangible or physical mass which preferably has considerable mass or inertia so that it may not be materially affected by or respond to a current of irregular or non-uniform frequency or of a frequency other than that of the circuit of the secondary s. 100

The band section F drives or sets into vibration the band section G, which is also a tangible or physical structure or mass, 105

having in general properties similar to those of the section F as to inertia, mass, and natural period. The band sections F and G are, in effect, mechanically coupled to each other, and this coupling, in a sense similar to coupling of electric circuits with each other, may be close or loose.

The mechanical coupling between the band sections F and G is the closer as the upper edge of the middle fulcrum *w* is the sharper or narrower as measured longitudinally of the band. When the upper edge of the fulcrum *w* is in effect a knife edge, the mechanical coupling between the sections F and G is close. A loose coupling between the sections may be effected by broadening or flattening the upper edge or end of the middle fulcrum *w*, as measured longitudinally of the band.

Furthermore, the flexibility of the band itself has an influence upon the closeness of coupling; for example, when the band is very flexible the coupling between the band sections will be loose, whereas when the band is relatively more rigid or stiff the coupling is the closer.

Loose coupling effects a higher degree of selectivity, as in the analogous case of loosely coupled electrical circuits. Loose coupling between the band sections F and G, and the other related band sections throughout this disclosure, may be obtained by employing a relatively flexible band and/or by making the upper edge of the fulcrum *w* flat or broad, at least as compared to a very sharp edge.

The coupling may be still further loosened, if suitable or desirable, by employing more than two band sections. Such an arrangement is indicated in Fig. 7, where between the band sections F and G there are three additional band sections, all preferably of the same natural period with F and G, the upper edges of the four intermediate fulcra *w* being, if suitable or desirable, suitably flattened or broadened.

The band section G, Fig. 1, driven by the band section F, drives and vibrates the armature *j* of the associated magnet system, of which the upstanding members *k* may be of magnetizable material, at a frequency corresponding with the frequency of vibration of the section G, thereby causing induction or generation in the windings *d* of a current whose frequency corresponds with the vibration frequency of the section G. This current in turn traverses the windings *d* of the magnet system associated with the band section F¹ of the second band system, causing the armature *j* to vibrate at like frequency and drive and vibrate the band section F¹ at like frequency. The section G¹, preferably loosely coupled to the section F¹, is driven by F¹ and in turn drives and vibrates the armature *j* of the

system associated with section G¹ at similar frequency, causing generation or induction in its windings *d* of current of like frequency, which traverses the primary *x* and induces in the secondary *y* a current of corresponding frequency which is then amplified, if desired, and impressed upon the translating instrument T, which, if a telephone, will produce a sound or note corresponding with the frequency of the current delivered thereto by the secondary *y*, which frequency corresponds with the frequency of the current, however produced as above described, in the secondary *s* or other equivalent or suitable receiving circuit.

By the method and apparatus described, undesired signals and the disturbing effects of static, strays, atmospherics or other natural electrical effects are selectively excluded. Static or other natural electrical disturbance occurs with irregularity or non-uniform frequency, and the response of the band structure is accordingly feeble, and tone selectivity and the anti-static property of the band system are both increased by increase in inertia of the primary band, as F.

While I have described the employment of two or more band systems in cascade, it will be understood that a single band system may be employed, though band systems in cascade effect ultimate higher selectivity.

It will further be understood that my invention is not limited to the employment of beats at the receiving station, but that any type of receiving apparatus may be employed which effects a current of definite or uniform frequency in the circuit of the coils *d* associated with the band section F. If the received energy is that of continuous or sustained waves, it may be broken up into uniformly spaced groups, the duration of each group preferably being small or short compared with the duration of the shortest element of the telegraphic signal, as a dot. For example, by a so-called chopper or ticker the received sustained oscillations may be broken up into groups succeeding each other at the rate of 1000 per second, or at any other suitable rate.

The system is equally applicable to the case where the received sustained oscillations are modulated or varied in amplitude by a tone circuit or tone wheel. And the system is also utilizable in the case where at the transmitting station the sustained oscillations are caused to rise and fall in amplitude at a uniform or definite frequency, preferably audible frequency, by the effect of a tone circuit, tone wheel, beat production or equivalent. The receiving apparatus is also utilizable in the case where the energy at the transmitting station is of constant amplitude, but in-

terrupted or broken up into wave groups at definite or uniform frequency. And in the case of spark transmitters, my selective apparatus is utilizable in case the sparks succeed each other at definite or uniform frequency, to which frequency will then be attuned, as in the other cases, the audio frequency circuits and the band sections.

Therefore, in general, it will be understood that my invention is not limited to any particular type of transmitting or receiving apparatus, but comprehends, generically, the production in the winding of a magnet system of a band, reed or equivalent device of a current, however caused or produced, of definite or uniform frequency to which the band, reed or equivalent is preferably attuned.

Since each of the band systems or equivalent has considerable mass or inertia, once it is set into vibration by the associated magnet system or by a driver band section or equivalent, it will tend to continue in vibration for a considerable period, since its vibration decrement is relatively small, especially as compared with usual electrical circuits, owing to the tension, mass and stiffness or rigidity of the band. This property or characteristic of persistence of vibration on the part of the mechanical system causes reverberation, with resulting blurring or indistinctness of the immediately succeeding signal elements. To prevent undesirable degree of reverberation or blurring, damping of the band or equivalent is resorted to.

In the system described, this damping is effected electro-dynamically by tuning, as by condensers C^2 , C^4 and C^5 , the circuits of the coils or windings d . With these circuits tuned to the frequency of the band sections with which they are associated, the kinetic energy of vibration of the band sections after cessation of the current or force which causes such vibration is consumed in generating or producing in the circuits currents of relatively high magnitude, due to the tuning or resonant effects, and the production or dissipation of such energy acts to dampen or quickly reduce the amplitude of the vibrations of the band sections.

This electro-dynamic damping is referred, and the tuning of the circuits as aforesaid, in addition to effecting damping, serves also to cause the electric circuits to respond resonantly and cumulatively to the currents in them during the signal-producing time or period.

While electro-dynamic damping or braking is preferred, it will be understood that any other suitable method or means for damping may be employed.

Referring to Figs. 4 and 5, there is associated with each or any band section, as F , the divided magnetic poles z and a^1 of a magnet system comprising the core b^1 and

yokes c^1 , the end of one of these yokes c^1 terminating in the pole structure z consisting of two parts spaced from each other to permit passage of the aforesaid rod a . The system is excited by the winding d^1 traversed by uni-directional or direct current from any suitable source. The pole a^1 is adjustable by the screw e^1 toward and away from the band section F , so that the band shall be equally spaced between the upper and lower poles, whereby the band is normally not subjected to mechanical strain by either pole, since the fluxes act equally and oppositely upon the band, which by preference may be low resistance magnetic material. After the band F has been set into vibration by a signal-representing current, and the band is vibrating due to its persistency or inertia, the magnet system will act upon the band to dampen it, due to the magnetic fields established within the band and setting up therein eddy currents which effectively dampen its motion. This type of magnetic damping does not change the selectivity of the band. When the band is under strain by flux of the damping magnet system z , a^1 , there exists a condition analogous to resistance damping in electrical circuits, and selectivity is reduced; but the poles z and a^1 normally exert zero strain upon the band.

In Fig. 6 is shown a mechanical damping system in which a spring f^1 bears upon the band through the pad g^1 of the felt or other suitable material. The pressure or tension exerted by the spring is adjustable by the screw h^1 .

A receiving system with which the band system is utilizable may be of the general type or character indicated in Fig. 2, wherein there is employed a double audion or thermionic detector structure V^1 , whose grids g are simultaneously subjected to the same potential due to received energy and the effects of static, atmospherics, etc., through the windings S^1 , S^2 , to which there is inductively coupled a primary P^1 traversed by sustained radio frequency oscillations generated by the vacuum tube oscillator V^2 . The circuits of the anodes a , a of the thermionic structure V^1 include audio frequency transformer primaries p^1 and p^2 , inductively coupled to the secondary s , which latter and the associated band system, etc., correspond in structure and mode of operation in a general way with that described in connection with Fig. 1. So far as concerns detector action and the influence of received energy and static or atmospherics, their effect upon the secondary s is balanced out or substantially nil, whereas the beats, preferably of audio frequency, produced between the received signal energy and the oscillations produced by the oscillator V^2 , cumulatively affect the secondary s . It follows, therefore, that the effects of static, atmos-

pherics, etc. are further eliminated before reaching the band system by rendering nil the effect of the detector action upon the secondary s , and reducing the effect of static and 5 equivalent effects, from the fact that they do not from the sustained oscillations produced by the oscillator V^2 produce regular or substantial beats, but, on the other hand, produce, if anything, a feeble effect upon the 10 secondary s .

Accordingly, static and corresponding effects are materially reduced, and there exists then in the secondary s and the circuits associated therewith current or audio frequency 15 corresponding with the frequency of the beats produced, and these are then caused to affect the band device F , which in turn affects the band section G , which in turn affects the instrument T , the band system, 20 as well as the above described static-reducing system, contributing to effective elimination of static and other irregular and undesired effects.

The system in Fig. 3 is similar to that described in connection with Fig. 2, except, however, that the received energy reacts with that of the thermionic oscillator V^2 to produce beats, preferably of inaudible frequency, by reaction with the received signal energy, and the static and other effects producing imperfect and irregular beats therewith, with the result that in the secondary S^3 there is reduced effect of static and the like, though the beats formed with the signal energy are uniform and pronounced. 30 These beat currents impress upon the grids g of a thermionic device V^1 , through the windings S^1 and S^2 , similar potentials, with the result that the detector effect of these primary beats upon the secondary s is practically nil. The thermionic oscillator V^2 produces sustained oscillations of a frequency 40 which react with the primary beat frequency to produce secondary beats of preferably audio frequency, which, however, as in Fig. 2, cumulatively affect the secondary s , which latter is associated with windings d and a band system such as described in Figs. 1 and 2.

In Figs. 2 and 3 the primary P^1 is preferably rotatable or movable with respect to the windings S^1 , S^2 , in order suitably to adjust the amplitude of the energy from the oscillator V^2 to the amplitude of the signal-representing oscillations or currents in the windings S^1 and S^2 , it being preferred, generally, that the amplitudes be approximately equal.

While, as indicated in Figs. 1 and 2, it is preferred that the vibrating mechanical member, as F , shall drive or set into vibration a second mechanical member, as G , it will be understood that the two armatures of the two systems involving the coils d ; that is, the primary or driver system and the

secondary or generator system, may be associated with one and the same vibrating member which, as indicated in Fig. 8, may be a reed, tuning fork or equivalent device R , attuned to the frequency of the current 70 traversing the primary or driver coil system, which, in Fig. 8, is at the left, while the generator or secondary electrical system is at the right.

Or, as indicated in Fig. 9, a single band F 75 may co-act with the magnet systems of the primary or driver circuit and the secondary or generator circuit.

When so using a single mechanical vibrating member, the armatures of the driver and 80 secondary systems may be connected to the mechanical vibrating member, at the same point, as indicated in Fig. 8, or at different points, as indicated in Fig. 9.

In Fig. 10 the coupling between the magnet systems of the driver or primary circuit and the secondary or generator circuit is effected through an air column contained within the telescoping tube sections I , J closed, respectively, by the diaphragms K 90 and L . These diaphragms may or may not be resonant or tuned to the frequency of the currents which they respectively respond to and generate. However, the air column is 95 attuned to the driver or primary frequency.

In this arrangement the current of audio frequency in the driver or primary coils d vibrates the diaphragm K at corresponding frequency, setting up in the tuned air column vibrations of the same frequency, which in 100 turn vibrate the diaphragm L at similar frequency, with the result that there is generated in the secondary or generator circuit current of corresponding frequency, which may then be amplified and delivered to a translating 105 device, as T , Fig. 1, or there may intervene a second air column system corresponding to the second band system F^1 , G^1 of Fig. 1.

The air column in Fig. 10 effects a substantially loose mechanical coupling between 110 the driver and secondary systems, and is also effective in reducing effects of currents of undesired frequencies or of irregularly or non-uniformly spaced currents, as those due to static, etc.

While in the foregoing description I have referred to the tuned mechanical elements, as the bands, reeds and air column, as having a period resonant with the driver or primary frequency, it shall be understood that these 120 mechanical vibrating members may be dissonant or out of tune with the current frequency. For example, in Figs. 1 and 2, the band sections F and F^1 , in Figs. 8 and 9 the reed R and band F , and in Fig. 10 the air 125 column, may have a natural frequency different from that of the driver or primary current, whereby such current forces in the mechanically vibrating member vibrations at the primary or driver frequency, and the 130

generator or secondary circuit in resonance with the driver or primary current is actuated or controlled by the dissonant mechanically vibrating member whose oscillations are forced. More particularly, as regards Figs. 1 and 2, the band section F may be dissonant to the frequency of the driver current from the secondary S, while the second band section G may be resonant to the frequency of the current supplied by the secondary S. And the same may be the relation between the bands F¹ and G¹ of Fig. 1. In other words, the driver sections may be dissonant to the currents actuating them while the secondary band sections G and G¹ may be resonant to such current.

Or with a primary band section resonant to the driving frequency, the secondary section may be dissonant and the secondary electric circuit may be resonant to the primary frequency or resonant to the frequency of the secondary mechanical section.

While I have herein referred to the frequency of the driver or primary current and that of the band section or other mechanically vibrating element as equal, it will be understood that the frequencies may be unequal in the sense that one may be any suitable multiple of the other. And this applies also to the secondary or driven mechanical elements, as G, G¹, Fig. 1. Furthermore, the arrangement may be made such that the frequency of the currents in the primary or driver and secondary or generator circuits are unequal, as by making one of them a multiple of the other.

It will further be understood that it is within the skill of the art to interpose between the secondary s or other source of driver or primary current and the magnet system which drives the mechanical vibrating member one or more stages of amplifiers similar to the arrangement of H, H in Figs. 1 and 2. And where cascade arrangement of band or vibrating systems is employed, as in Fig. 1, one or more amplifiers may be introduced between the generator or secondary coils d, d of one band system and coils d, d of the driver or primary system of the second band system.

It will further be understood that my invention is not limited to the dynamo-electric generation of current in the secondary or generator circuit, but comprehends also the production or generation of the current in the secondary system by any other method or means, as for example, by varying the resistance or impedance of a circuit including a source of energy, whereby there are fluctuations of amplitude of the current equal to or corresponding with the frequency of the mechanically vibrating member.

For brevity in the appended claims, it shall be understood that reference to resonance or tuning of a mechanical system or

member to another mechanical system or member, and to a periodic current, is not limited to equality of frequencies, but includes also such other relation of the frequencies as will produce the effects herein described.

What I claim is:

1. The method of selectively receiving electrical signal energy, which consists in vibrating by a periodic signal-representing current a mechanical system resonant to the frequency of said current, generating a secondary current by said vibratory mechanical system, and translating said secondary current.

2. The method of selectively receiving electrical signal energy, which consists in vibrating by a periodic signal-representing current a mechanical system resonant to the frequency of said current, generating by said mechanical system a secondary current of a frequency corresponding with the frequency of said vibrating system, and translating said secondary current.

3. The method of selectively receiving electrical signal energy, which consists in vibrating by a periodic signal-representing current a mechanical system resonant to the frequency of said current, generating by said vibratory system a secondary current of a frequency corresponding with the frequency of said periodic signal-representing current, and translating said secondary current.

4. The method of selectively receiving electrical signal energy, which consists in vibrating a mechanical system by a periodic signal-representing current, generating by said mechanical system a secondary current having a frequency corresponding with said periodic signal-representing current, reinforcing said secondary current by electrical resonance, and translating said reinforced secondary current.

5. The method of selectively receiving electrical signal energy, which consists in vibrating by a periodic signal-representing current a mechanical system having a natural period corresponding with the period of said signal-representing current, generating by said mechanical system a secondary current of a frequency corresponding with the frequency of said vibrating system, reinforcing said secondary current by electrical resonance, and translating said reinforced secondary current.

6. The method of selectively receiving electrical signal energy, which consists in vibrating by a periodic signal-representing current a mechanical system having a natural period corresponding with the period of said signal-representing current, generating by said mechanical system a current having a frequency corresponding with the frequency of said periodic signal-representing current, reinforcing said

secondary current by electrical resonance, and translating said reinforced secondary current.

7. The method of selectively receiving 5 electrical signal energy, which consists in controlling vibration of a mechanical system by a periodic signal-representing current, vibrating a second mechanical system by said first mechanical system, generating 10 by said second mechanical system a vibratory current, and translating said last named current.

8. The method of selectively receiving 15 electrical signal energy, which consists in controlling vibration of a mechanical system by a periodic signal-representing current, vibrating a second mechanical system by said first mechanical system loosely coupled thereto, generating by said second mechanical 20 system a vibratory current, and translating said last named current.

9. The method of selectively receiving 25 electrical signal energy, which consists in controlling vibration of a mechanical system by a periodic signal-representing current, vibrating a second mechanical system by said first mechanical system, at least one 30 of said mechanical systems having a natural period corresponding with the period of said signal-representing current, generating by said second mechanical system a vibratory current, and translating said last named current.

10. The method of selectively receiving 35 electrical signal energy, which consists in controlling vibration of a mechanical system by a periodic signal-representing current, vibrating a second mechanical system by said first mechanical system, said mechanical 40 systems having equal natural periods of vibration, generating by said second mechanical system a vibratory current, and translating said last named current.

11. The method of selectively receiving 45 electrical signal energy, which consists in controlling vibration of a mechanical system by a periodic signal-representing current, vibrating a second mechanical system by said first mechanical system, said mechanical 50 systems having periods of vibration corresponding with the period of said signal-representing current, generating by said second mechanical system a vibratory current, and translating said last named current.

12. The method of selectively receiving 55 electrical signal energy, which consists in controlling vibration of a mechanical system by a periodic signal-representing current, vibrating a second mechanical system by said first mechanical system, generating by said second mechanical system a vibratory current whose frequency corresponds with the frequency of said signal-representing

current, and translating said last named 65 current.

13. The method of selectively receiving 70 electrical signal energy, which consists in controlling vibration of a mechanical system by a periodic signal-representing current, vibrating a second mechanical system by said first mechanical system, generating by said second mechanical system a vibratory 75 current whose frequency corresponds with the frequency of said first mechanical system, and translating said last named current.

14. The method of selectively receiving 80 electrical signal energy, which consists in controlling vibration of a mechanical system by a periodic signal-representing current, mechanically vibrating a second mechanical system by said first mechanical system, generating by said second mechanical 85 system a vibratory current whose frequency corresponds with the frequency of said mechanical systems and said signal-representing current, and translating said last named current.

15. The method of selectively receiving 90 electrical signal energy, which consists in controlling vibration of a mechanical system by a periodic signal-representing current, mechanically vibrating a second mechanical system by said first mechanical system, generating by said second mechanical system 95 a vibratory current, vibrating a third mechanical system by said vibratory current, producing by said third mechanical system a vibratory current, and translating said last named current.

16. The method of selectively receiving 100 electrical signal energy, which consists in controlling vibration of a mechanical system by a periodic signal-representing current, 105 mechanically vibrating a second mechanical system by said first mechanical system, controlling by said second mechanical system production of a vibratory current, vibrating a third mechanical system by said vibratory 110 current, mechanically vibrating a fourth mechanical system by said third mechanical system, producing a vibratory current by said fourth mechanical system, and translating said last named current.

17. Electrical signal receiving apparatus 115 comprising a source of periodic signal-representing current, a vibrating member having a natural period corresponding with the period of said signal-representing current 120 and vibrated thereby, means for generating a vibratory current by said member, and a signal-translating instrument controlled by said generated current.

18. Electrical signal receiving apparatus 125 comprising a source of periodic signal-representing current, a member vibrated by said current, a circuit, means for generating

in said circuit by said member a current having a frequency corresponding with the frequency of said signal-representing current, means for rendering said circuit resonant to said frequency, and a signal-translating instrument controlled by said circuit.

19. Electrical signal receiving apparatus comprising a circuit, means for causing in said circuit a periodic signal-representing current, a member vibrated under control of said current and having a natural period corresponding with the period of said signal-representing current, means for damping the vibrations of said member, a second circuit, means for producing in said second circuit a vibratory current under the control of said member, and a signal-translating instrument controlled by said second circuit.

20. Electrical signal receiving apparatus comprising a circuit, means for causing in said circuit a periodic signal-representing current, a member vibrated under control of said current and having a natural period corresponding with the period of said signal-representing current, means for damping the vibrations of said member comprising means for tuning said circuit to the period of said member, a second circuit, means for producing in said second circuit a vibratory current under the control of said member, and a signal-translating instrument controlled by said second circuit.

21. Electrical signal receiving apparatus comprising a circuit, means for causing in said circuit a periodic signal-representing current, a vibrating member, electro-magnetic means controlled by the current in said circuit for actuating said member, means for damping said member comprising means for tuning the circuit of said electro-magnetic means, means controlled by said vibrating member for producing a vibratory current, and means for translating said vibratory current.

22. Electrical signal receiving apparatus comprising a source of periodic signal-representing current, vibratory members mechanically coupled to each other, means for vibrating one of said members under control of said signal-representing current, means for producing a vibratory current under the control of another of said vibratory members, and means for translating said vibratory current.

23. Electrical signal receiving apparatus comprising a source of periodic signal-representing current, vibratory members loosely mechanically coupled to each other, means for vibrating one of said members under control of said signal-representing current, means for producing a vibratory current under the control of another of said vibratory members, and means for translating said vibratory current.

24. Electrical signal receiving apparatus

comprising a source of periodic signal-representing current, vibratory members mechanically coupled to each other and at least one of them having a natural period corresponding with the period of said signal-representing current, means for vibrating one of said members under the control of said signal-representing current, means for producing a vibratory current under the control of another of said vibratory members, and means for translating said vibratory current.

25. Electrical signal receiving apparatus comprising a source of periodic signal-representing current, vibratory members loosely mechanically coupled to each other and at least one of them having a natural period corresponding with the period of said signal-representing current, means for vibrating one of said members under the control of said signal-representing current, means for producing a vibratory current under the control of another of said vibratory members, and means for translating said vibratory current.

26. Electrical signal receiving apparatus comprising a source of periodic signal-representing current, mechanically coupled vibratory members having natural periods corresponding with the period of said signal-representing current, means for vibrating one of said members under control of said signal-representing current, means for producing a vibratory current under the control of another of said vibratory members, and means for translating said vibratory current.

27. Electrical signal receiving apparatus comprising a source of periodic signal-representing current, coupled vibratory members, means for vibrating one of said members under control of said signal-representing current, means for producing a vibratory current under control of another of said members, means for damping the vibrations of said other of said members, and means for translating said vibratory current.

28. Electrical signal receiving apparatus comprising a source of periodic signal-representing current, coupled vibratory members, means for vibrating one of said members under control of said signal-representing current, means for producing a vibratory current under control of another of said members, means for damping the vibrations of said other of said members comprising means for rendering resonant the circuit of said vibratory current-producing means, and means for translating said vibratory current.

29. Electrical signal receiving apparatus comprising a source of periodic signal-representing current, coupled vibratory members, means for vibrating one of said mem-

bers under control of said signal-representing current, a circuit, means for electro-dynamically generating a current in said circuit by another of said vibratory members, and means for damping the vibrations of said other of said members comprising means for rendering said circuit resonant to a frequency corresponding with the natural frequency of said other of said members.

30. Electrical signal receiving apparatus comprising a circuit traversed by periodic signal-representing current, mechanically coupled vibratory members having a vibration frequency corresponding with the frequency of said signal-representing current, electro-magnetic means in said circuit for vibrating one of said members, means for tuning said circuit to the vibration frequency of one of said members, a second circuit, means for producing therein a periodic current of frequency corresponding with the vibration frequency of another of said members, means for tuning said second circuit to the vibration frequency of said other of said members, and a translating instrument controlled by said second circuit.

31. Electrical signal receiving apparatus comprising a source of periodic signal-representing current, a band vibrating in sections, means for vibrating one of said sections under control of said signal-representing current, means for producing a vibratory current under the control of another of said sections, and a translating instrument affected by said vibratory current.

32. Electrical signal receiving apparatus comprising a source of periodic signal-representing current, a band vibrating in sections loosely coupled to each other, means for vibrating one of said sections under control of said signal-representing current, means for producing a vibratory current under the control of another of said sections, and a translating instrument affected by said vibratory current.

33. Electrical signal receiving apparatus comprising a band vibrating in sections, a circuit traversed by periodic signal-representing current, electro-magnetic means in said circuit for vibrating one of said band sections, means for tuning said circuit to the frequency of said signal-representing current, a second circuit, means for producing therein a vibratory current by another of said band sections, means for tuning said second circuit to the vibration frequency of the current produced therein, and a signal-translating instrument controlled by said second circuit.

34. Electrical signal receiving apparatus comprising a band vibrating in sections loosely coupled to each other, a circuit

traversed by periodic signal-representing current, electro-magnetic means in said circuit for vibrating one of said band sections, means for tuning said circuit to the frequency of said signal-representing current, a second circuit, means for producing therein a vibratory current by another of said band sections, means for tuning said second circuit to the vibration frequency of the current produced therein, and a signal-translating instrument controlled by said second circuit.

35. Electrical signal receiving apparatus comprising a band vibrating in sections, a circuit traversed by periodic signal-representing current, electro-magnetic means in said circuit for vibrating one of said band sections, means for tuning said circuit to the frequency of said signal-representing current, a second circuit, means for producing therein a vibratory current by another of said band sections, means for tuning said second circuit to the vibration frequency of the current produced therein, and a signal-translating instrument controlled by said second circuit, said band sections having natural periods corresponding with the period of said signal-representing current.

36. Electrical signal receiving apparatus comprising a band vibrating in sections, a circuit traversed by periodic signal-representing current, electro-magnetic means in said circuit for vibrating one of said band sections, means for tuning said circuit to the frequency of said signal-representing current and the natural frequency of said one of said band sections, a second circuit, means for electro-dynamically generating therein a vibratory current by another of said band sections, means for tuning said second circuit to the frequency of said other band section, and a translating device controlled by said second circuit.

37. The combination with a source of periodic signal-representing current, of means producing a periodic current reacting with said signal-representing current to produce beats, mechanically coupled vibratory members, a circuit traversed by current of beat frequency for vibrating one of said members, means for producing a vibratory current under the control of another of said members, and a device for translating said vibratory current.

38. The combination with a source of periodic signal-representing current, of a circuit, means for rendering substantially nil the direct effect of said current upon said circuit, means producing a periodic current of different frequency reacting with said signal-representing current to produce beats, means for affecting said circuit by said beats, a vibratory member vibrated under the control of said circuit, vibratory

current-producing means controlled by said member, and a device for translating said vibratory current.

39. The combination with a source of periodic signal-representing current, of means producing vibratory current of different frequency reacting with said signal-representing current to produce beats, a circuit, means for rendering the effect of said beats upon said circuit substantially nil, a second source of current of frequency differing from the frequency of said beats reacting with the current having the frequency of said beats to produce secondary beats, means for rendering said secondary beats effective in said circuit, a vibratory member vibrated under the control of said circuit, means for producing a vibratory current under the control of said vibratory member, and means for translating said vibratory current.

40. The combination with a source of periodic signal-representing current, of a resonant vibratory member vibrated by said current, signal-translating means controlled by said vibratory member, and means for damping said member comprising means for electro-dynamically generating thereby a damping current.

41. The combination with a source of periodic signal-representing current, of a resonant vibratory member vibrated by said current, signal-translating means controlled by said vibratory member, means for damping said member comprising means for electro-dynamically generating thereby a damping current, and means for reinforcing said damping current by electrical resonance.

42. The combination with a source of periodic signal-representing current, of a resonant vibratory member vibrated in accordance with said current, a circuit, and means for generating in said circuit by the vibrations of said member a damping current.

43. The combination with a source of periodic signal-representing current, of a resonant vibratory member vibrated in accordance with said current, a circuit, means for generating in said circuit by the vibrations of said member a damping current, and means associated with said circuit for reinforcing the damping current by electrical resonance.

44. The combination with a source of signal-representing current, of a resonant vibrating member controlled thereby, a second resonant vibratory member coupled with and vibrated under the control of said first-named vibratory member, signal-translating means controlled by said second vibratory member, and means for damping the vibrations of said members upon cessation of signal-representing current comprising means for generating thereby electrical damping energy.

45. The combination with a source of signal-representing current, of a resonant vibrating member controlled thereby, a second resonant vibratory member coupled with and vibrated under the control of said first-named vibratory member, signal-translating means controlled by said second vibratory member, means for damping the vibrations of said members upon cessation of signal-representing current comprising means for generating thereby electrical damping energy, and means for reinforcing said damping energy by electrical resonance.

46. Electrical signal-receiving apparatus comprising a source of periodic signal-representing current, mechanically coupled vibratory members, means for vibrating one of said members under control of said current, means controlled by another of said vibratory members for effecting periodic variations of current amplitude, and means for translating said last named current.

47. Electrical signal-receiving apparatus comprising a source of periodic signal-representing current, mechanically coupled resonant vibratory members, means for vibrating one of said members under control of said current, means for electro-dynamically generating by another of said vibratory members a periodic current, and means for translating said last named current.

48. Electrical signal-receiving apparatus comprising a circuit traversed by periodic signal-representing current, an armature controlled by said circuit, a signal-translating circuit, a second armature associated with said second named circuit, and a resonant vibratory mechanical system connecting said armatures.

49. Electrical signal-receiving apparatus comprising a resonant vibratory mechanical system, means for vibrating said system under the control of signal-representing current, an armature mechanically connected to said system and vibrated thereby, and a signal-translating circuit in which movement of said armature generates a periodic electro-motive-force.

50. Electrical signal-receiving apparatus comprising a resonant vibratory mechanical system, means for vibrating said system under the control of signal-representing current, an armature mechanically connected to said system and vibrated thereby, a signal-translating circuit in which movement of said armature generates a current, and electrical means for tuning said circuit to reinforce the current generated therein.

51. Electrical signal-receiving apparatus comprising a resonant vibratory mechanical system, an armature mechanically connected to said system for vibrating it, a circuit traversed by periodic signal-representing current for vibrating said armature, and

signal-translating means controlled by said vibratory system.

52. Electrical signal-receiving apparatus comprising a resonant vibratory mechanical system, an armature mechanically connected to said system for vibrating it, a circuit traversed by periodic signal-representing current for vibrating said armature, signal-translating means controlled by said vibratory system, an armature mechanically connected to said system for vibrating it, a circuit traversed by periodic signal-representing current for vibrating said armature, and signal-translating means controlled by said vibratory system, said armature when vibrated by said vibratory system upon cessation of signal current generating in said circuit a periodic damping current.

10 53. Electrical signal-receiving apparatus comprising a resonant vibratory mechanical

system, an armature mechanically connected to said system for vibrating it, a circuit traversed by periodic signal-representing current for vibrating said armature, signal-translating means controlled by said vibratory system, said armature when vibrated by said vibratory system upon cessation of signal current generating in said circuit a periodic damping current, and means for reinforcing said damping current by electrical resonance.

In testimony whereof I have hereunto affixed my signature this 26th day of April, 1922.

DAVID G. McCAA.
